(57) **CLAIM**

We claim the ornamental design for an eye patch packaging, as shown and described.

DESCRIPTION

FIG. 1 is a top perspective view of a first embodiment of an eye patch packaging of the present invention;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a first side view thereof;

FIG. 8 is a second side view thereof;

FIG. 9 is a top perspective view of a second embodiment of an eye patch packaging of the present invention;

FIG. 10 is a bottom perspective view thereof;

FIG. 11 is a top view thereof;

FIG. 12 is a bottom view thereof;

FIG. 13 is a front view thereof;

FIG. 14 is a rear view thereof;

FIG. 15 is a first side view thereof; and,

FIG. 16 is a second side view thereof.

The ornamental design which is claimed is shown in solid lines in the drawings. Any broken lines in the drawings are for illustrative purposes only and form no part of the claimed design.
